DESIGN FOR A CASING FOR PRESSING OR PUNCHING MACHINES OR THE LIKE

Guy O. Conner, Wheeling, W. Va.

Application May 5, 1944, Serial No. 113,479

Term of patent 14 years

(Cl. D63—1)

To all whom it may concern:

Be it known that I, Guy O. Conner, a citizen of the United States, residing at Wheeling, West Virginia, have invented a new, original, and ornamental Design for a Casing for Pressing or Punching Machines or the like, of which the following is a specification, reference being had to the accompanying drawing, forming part thereof.

In the drawing, Figure 1 is a perspective view of a casing for pressing or punching machines or

the like and Figure 2 is a perspective view of the casing for pressing or punching machines or the like shown in Figure 1 but as viewed from the opposite side, such figures showing my new design.

I claim:

The ornamental design for a casing for pressing or punching machines or the like, substantially as shown.

GUY O. CONNER.
